America, New York, N. Y., a corporation of
Delaware

Application June 29, 1937, Serial No. 150,891

(Cl. 250—27)

19 Claims.

My invention relates to electron discharge devices, particularly to such devices which utilize an electron discharge concentrated into more or less well defined beams of electrons and which 5 may be operated either at the comparatively low voltages generally used in conventional receiving tubes or at considerably higher voltages.

10 Electron beams, usually small and circular in cross section, have been utilized principally in cathode ray tubes, such as X-ray tubes and cathode ray oscilloscopes, which operate at comparatively high voltages, in some cases several thousand volts, and in which usually only a small part 15 of the total emission from the cathode is concentrated into a beam. Electron discharge tubes have been proposed for use as relays, detectors, and similar purposes in which a similar electron beam is deflected in much the same way as in a cathode ray oscilloscope, but such tubes have 20 low efficiency and poor transconductance as compared with conventional types of tubes, hence such discharge tubes of the cathode ray type have been limited commercially to rather special fields 25 of use and are of little practical value at low voltages.

There are also at the present time electron discharge devices making use of the conventional helically wound grids which are aligned to reduce the current taken by the control electrodes during 30 operation of the devices. While in effect lined up grids produce more or less well defined beams, the control over the beam is limited and the current loss to the control electrodes while small in comparison to other types of tubes is still greater than is sometimes desired. In this type of tube 35 as the number of grids increases it becomes increasingly difficult to align the grids and this difficulty increases as the number of turns is increased in the control grid. In this type of electron discharge device the characteristics for optimum operation dictate the shape and position 40 of the electrodes. A change in the spacing of the grid wires of one grid necessitates changing the others, since otherwise the beams would be intersected by the other grid wires. Furthermore, 45 it is difficult to obtain a device of the conventional type having high plate current and an amplification factor or mu much less than 9.

One object of my invention is to provide electron discharge devices of the beam type which are efficient and utilize substantially all of the emission from a thermionic cathode and in which the total discharge from the cathode is formed 50 into a plurality of more or less well defined beams which are utilized in novel and effective ways to

obtain improved tubes having advantages unobtainable with the conventional types of structure used in electron discharge devices.

Another object of my invention is to provide improved electron discharge devices which are of much the same dimensions and are operated at much the same voltages as the conventional receiving tube, but which can be also effectively operated at higher voltages, and in which various desirable characteristics are obtained by segregating the space current into an electron beam or 10 beams and utilizing the properties of the beam to advantage.

A still further object is to provide an electron discharge device of the electron beam type which 15 is of greater efficiency and operates at lower voltages than the beam type devices heretofore used.

Another object of my invention is to provide an improved form of electron discharge device in which the characteristics for optimum operation 20 do not entirely dictate the shape and position of the electrodes, and in which a change in aperture in one control electrode will not necessarily require a corresponding change in the apertures in other control electrodes.

It is another object of my invention to provide an electron discharge device having a plurality of grids in which the grids can be easily aligned so as to reduce during operation of the tube the current to the control electrodes to a very small 30 value or to substantially zero.

Another object of my invention is to provide an electron discharge device of the beam type in which substantially complete control is maintained of the electron beams.

A further object is to provide an electron discharge device having a control grid or similar electrode which may be operated over a partly or continuously positive range of potentials with reference to the cathode and receive a current so 40 much reduced from that commonly obtained that the positive grid is substantially currentless during operation of the tube.

In a preferred embodiment of my invention I provide an electron discharge device having a cathode provided with a plurality of emitting surfaces and formed to assist in the formation of electron beams, and an anode for receiving the beams of electrons from the cathode. Between the cathode and anode are positioned in succession three slat type grids, that is, flat sheet grids having slots and including a zero or negatively biased grid near the cathode, a positively biased grid, and a third grid which may be at zero potential or at a slightly positive potential, the slots 50

of each of the grids registering with the slots in the other grids and with the emitting surfaces of the cathode. The cathode may comprise a plurality of individual cathode members in registry with the grid slots or a specially formed cathode which provides a plurality of beams. By properly shaping the slots or apertures in the grids and supplying the proper potentials to the various electrodes, I am able to obtain a highly efficient, high current, low μ tube which is particularly suitable for amplifying and power output purposes, and which has the other desirable characteristics referred to in the objects of the invention.

15 The novel features which I believe to be characteristic of my invention are set forth with particularity in the appended claims, but the invention itself will best be understood by reference to the following description taken in connection with the accompanying drawings in which Figure 1 is a diagrammatic representation of the electrode arrangement of a simple form of electron discharge device made according to my invention and a circuit connected thereto, Figures 2 to 7 inclusive are diagrammatic representations illustrating the action of an electron in various types of electric fields formed by different types of electrodes, Figure 8 is a perspective partly in section to show details of construction of an 20 electron discharge device made according to my invention, Figure 8a is a bottom view of the mount showing details of construction, Figure 9 is a transverse section taken along the line 9-9 of Figure 8, Figure 10 is a detailed showing in 25 perspective of a modified form of cathode construction, Figure 11 is a detailed showing in perspective of a form of grid used in the construction shown in Figure 8, Figure 12 shows the details of a mica spacer used in connection with 30 the grid shown in Figure 11 and the mount of the tube shown in Figure 8, Figure 13 is a diagrammatic representation of the electrode arrangement of another simple form of electron discharge device made according to my invention, 35 and a circuit connected thereto, and Figures 14 and 15 are curves showing the anode voltage-anode current characteristics of tubes made according to my invention.

In Figure 1 is diagrammatically shown the 40 electrode arrangement of a simple form of an electron discharge device employing the principles of my invention. The cathode 10 which may be of the indirectly heated type has on a restricted area, an electron emitting coating 11. 45 Following in succession are grids 12, 13 and 14 having apertures 12', 13' and 14' which are aligned, and an anode 15 suitably positioned which receives the beam of electrons from the cathode 10. The cathode 10 is shown as a 50 square tubular member indirectly heated but it may be of the directly heated filament type and the grids 12, 13 and 14 rectangular plates provided with rectangular apertures or slots coextensive with the coating 11 on the cathode 10. 55 The anode or plate 15 may be an imperforated rectangular electrode. It is understood of course that the electrode system may be duplicated on the other sides of the cathode so that a plurality of beams are formed. The electrode 12 60 may be at zero or negative potential with respect to the cathode and may be used as the control electrode. As shown, it is biased negatively with respect to the cathode. The second electrode, which is at a higher positive potential 65 70 75 may be used as an accelerating grid or screen

grid, or as a positively biased control grid in which case grid 12 acts as a beam forming and current adjusting electrode to form the electrons from the cathode into a beam of desired intensity. Grid 13 is shown used as a control grid, 5 the input circuit 10' being connected between it and the cathode 10. Grid 14 may be termed a suppressor grid or shield for controlling the formation of the beam between the grid 13 and anode 15 and to prevent the return of primary 10 electrons and for suppressing secondary electrons. Anode 15 may be connected to the output circuit 15'. The broken lines having the arrow heads represent the outline of the beam of electron, and the other lighter lines transverse to the broken lines represent equipotential surfaces or field force lines of the electric field between the various electrodes. The formation of the beam and the effect of the field on the electrons moving from the cathode to the anode 20 will be discussed in greater detail after consideration of some of the fundamental principles governing the movement of electrons in electric fields.

In Figure 2 is represented an electric field in 25 which the voltage increases in the direction of the movement of electrons from + to +++. Such a field is termed an accelerating field. The broken lines represent the path of electrons and the straight lines transverse to the broken lines 30 represent the points in space of the same potential. These last lines may be termed field force lines. An electron moving perpendicularly to the field force lines continues to move in a straight line. This is represented by broken 35 line a. If, however, the electron enters the field at some angle as indicated by lines b, c, d, or e, the electron is deflected from its original direction so that it travels on a curved path as shown. The greater the field gradient, that is 40 the greater the change in the field in the direction of the movement of the electron, the greater will be the curvature of the path of the electron until it assumes a direction at right angle to the field force lines.

In Figure 3 is represented an electric field in 45 which the gradient decreases, in other words one in which the potential decreases in the direction of the movement of an electron in the electric field. This is termed a decelerating field. Here 50 again as shown by the broken line a' an electron will continue to travel in a straight path perpendicular to the field force lines if this is its initial direction with respect to the field. If the electron enters the field at an angle as represented by b', c', d' and e' the electric forces tend to reverse the electron direction of movement in the same way that the opposing gravitational force tends to reverse the direction of a projectile shot into the air. If the angle is 55 great enough and the field strong enough the electron will make a complete reversal as is indicated by the broken line e'. These are the more simple movements of an electron in linear fields. The movement of the electrons becomes 60 somewhat more complicated in curved fields.

By the combination of various types of electrodes to which are applied various voltages, electron lens effects can be obtained which will influence a beam of electrons so that they may 65 be either focused or dispersed after leaving their source. The action under these conditions is diagrammatically shown in Figures 4 to 7 inclusive.

In Figure 4 the cathode 16, coated with emit- 75

ting material 17 for supplying the electrons, has spaced from it and at a lower potential an electrode 18 provided with an aperture 18'. The field potential to the right of the electrode 18 increases so that there is provided an accelerating field. The effect of this structure and the voltages applied are shown by the curved field force lines extending through the aperture 18' toward the cathode. In this arrangement the electron beam from cathode 16 is focused at some point *f* beyond the electrode 18 after which the beam disperses. Thus in an accelerating field, that is one which increases in potential in the direction of travel of the electron, an apertured electrode at less than space potential, that is, less than the potential which the field would normally have at the position of the electrode acts like a condensing lens which focuses the electron beam at some point beyond the electrode 20 in the direction of the movement of electrons. Because the space potential is increasing in the direction of electron flight, the lens effect produced may be referred to as an accelerating condensing lens.

25 In Figure 5 the electrode 18 is above space potential. Here the action of the field is to disperse the beam and increase its width so that no focusing results. In both Figures 4 and 5 it will be seen that the electrons tend to move 30 in paths at right angles to the field force lines and along the field gradient. The resulting lens effect of the arrangement in Figure 5 may be referred to as an accelerating dispersing lens.

In Figure 6 there is shown an apertured electrode in a decelerating field and below space potential. Here again the action of the field on the electron beam is to focus the beam as indicated by the broken lines toward a point beyond the electrode in the direction of the travel 40 of the electron. The resulting lens effect may be referred to as a decelerating condensing lens.

In Figure 7 the electrode 19 is in a decelerating field and above space potential, causing dispersion of the electron beam as indicated by the broken lines. The resulting lens effect may be referred to as a decelerating dispersing lens. Various combinations can thus be formed and by the application of the proper voltages either a condensing lens or a dispersing lens can be provided for effecting the electron beam either to converge the beam to a point or to disperse the beam. Thus an apertured electrode at a potential lower than space potential produces a focusing action while an electrode at a potential higher than space potential produces a dispersing action.

The field distribution and movement of the electrons as shown in Figure 1 can now be better understood. The electrode 12 is at a potential 60 which is that of the cathode or at some lower potential, while electrode 13 is at a higher potential than the cathode. This produces conditions equivalent to the condition shown in Figure 4 so that a focusing action results. Electrode 13 also functions to accelerate the electrons toward the electrodes 14 and 15. The aperture 13' in electrode 13 is sufficiently large to permit the beam to pass through without any substantial number of the electrons directly hitting this electrode. The third electrode 14, which is at a lower potential than electrode 13, but preferably at some slight positive potential, causes the field distribution between the electrode 14 and the anode 15 to be as indicated by 70 the light curved lines and helps to form a sec-

ond condensing lens to prevent excessive dispersion of the beam which diverges beyond the point *g*. The results at this point are similar to the condition shown in Figure 6. The beam of course does not focus to a point but has some 5 width at the cross-over or focus *g*.

The prevention of electron dispersion by insertion of element 14 is desirable to prevent the undesirable consequences of a too divergent beam, which would permit many primary electrons to be returned to the grid, see for example path *e*' in Figure 3.

To obtain an efficient beam tube it is necessary first that the beam width should be smaller than any slot width of any positive element, to 15 prevent the interception of electrons, and secondly, that the electrons should not be permitted to return to auxiliary positive electrodes. These conditions are satisfied by the construction shown in Figure 1 in which the electrons 20 are so focused that they are not intercepted by the electrodes 13 or 14, and the potential on electrode 14 and consequently the space potential between 14 and 15 is sufficiently less than that of the anode 15 so that secondaries produced at the plate 15 are prevented from returning to any of the positive grids.

Where the potential on grid 14 is less than that on grid 13, being only slightly higher than that of the cathode 10 and lower than that on the anode 15, as is the case in Figure 1, a high current tube is obtained with substantially no grid current. Substantially complete suppression of secondary emission is also obtained. In this case, where 14 is at a lower potential than 35 13, the slot width 14' must be larger than 13' as shown in Figure 1.

By decreasing the width of the slot in electrode 12, the other conditions remaining the same, the distance from the cathode of the focal 40 point of the beam is decreased. This increases the dispersion beyond the positive screen and may result in undesirable grid current due to the greater number of electrons returned to the positive grids after passing through. A short focal length is desirable to get a narrow beam at cross-over or focus, so that small apertures can be used in the grids and as a result better control over the beam. The most desirable focal length is one that gives the best balance between 45 50 the control effect of applied potentials and waste current percentage.

I have found that the structure shown in Figure 1 is the simplest and produces substantially optimum results. It is of course possible by the 55 introduction of other grids between grid 14 and the anode 15 to produce other results. The plate-impedance in tubes of this type can be controlled entirely by the beam formation in the structure and it may have any value, even negative values regardless of the electrostatic mu values of the grid or control electrode structures. The structure shown in Figure 1 might be described as a lens system having one accelerating lens produced by positively biased grid 13 and 60 65 a shielding element grid 14. This lens system has been found quite effective in preventing the return of electrons having wide angle paths. The No. 3 grid shields the divergent decelerated beam of primary electrons from the accelerating grid 70 member 2, simultaneously serving as suppressor for secondary electrons, thus reducing the number of necessary elements to five; that is, cathode, anode, and three grids.

In some cases where the structure shown in 75

Figure 1 is used with small plate currents as for example in radio frequency operation, it may be desirable to use a fourth or a suppressor grid to decrease the plate to control grid capacity 5 and prevent secondary emission as the space charge in the beam which helps in suppression of secondary electrons becomes too small with small anode currents.

By means of the arrangement described in Figure 1 it is possible to collect with a very low voltage applied on the anode 15 substantially all of the available current from the cathode 10 without loss of current to any of the positive control electrodes. This results in a low control-to-screen grid mu, high current output power tube which is of simple construction and easily made. A reasonable change in the slot width of one electrode need not materially affect the arrangement or construction of the other 15 electrodes in the tube since it is possible by the proper application of potentials to the electrodes to obtain the desired field and electron beam formation, which could not be done in conventional tubes using the conventional helically wound grids. For best results the slot in grid 12 should be coextensive with the emitting surface 11 on the cathode 10. The slot in grid 13 should be smaller than that in grid 12 but not so small as to intercept electrons. The slot 14' 20 in grid 14 is wider than that in the other grids but not so wide that the grid loses its shielding ability and permits secondary electrons or returned primary electrons to reach grid 13. It is possible with this arrangement, because of the 25 small beam width formed, to obtain effective control over the current and to reduce the loss within the tube to a very small value. Furthermore the positive electrode 13 can be used as a control grid with very low grid current 30 losses, because the beam is focused through the slot 13'.

In Figure 13 I show another simple form of electrode arrangement made according to my invention. The electrode arrangement comprises 45 a cathode 80 having an emitting coating 80' and grids 81, 82, 83 and 84 positioned between the cathode and the anode 85 and having registering apertures 81', 82', 83' and 84'. In this arrangement positive voltages are applied to both 50 grids 82 and 83, the grid 83 being at the higher positive potential. With this arrangement I provide a high current tube of similar characteristics to that shown in Figure 1 and having a low first to second grid mu. In this case the slot 55 width in grid 83 is reduced to or made less than the slot width 82' in grid 82 to obtain a good electron lens. Without the grid 84, the high voltage on the second accelerating grid, however, would cause slightly more grid current and 60 increased power loss although still considerably smaller than in conventional tubes. In order to remedy this last condition I use another or fourth grid 84 between grid 83 and the anode 85 to act as a suppressor for secondary electrons. 65 A proper balance should be reached between the various factors and it has been found that with the structure shown in Figure 13 where grids 82 and 83 are at a positive potential, grid 83 being at the higher potential, the best results are obtained when the ratio of the voltage 70 on grid 83 with respect to the voltage on grid 82 is equal to 2.5, with the slot 83' being reduced to the width of slot 82' and with the additional suppressor electrode 84 having a slot 75 width greater than the slots in any of the other

grid electrodes but not so large that it loses its shielding and suppressing ability. With a higher ratio than 2.5 the beam divergence beyond the focus h is smaller than the convergence angle before the focus. The beam, however, is dispersed again to some extent near grid 83 which would result in increased grid current. This, however, is neutralized by increasing the voltage on the anode or decreasing the slot width of grid 83 or both. However, the slot must not be made 10 such that it interferes with the beam. Where the voltages are applied to grid 82 and 83, as just described, the additional suppressor grid 84 is necessary to prevent return of secondaries. Grid 82 may, however, be shaped with a narrow 15 deep aperture and thus have the combined effect of grids 82 and 83, making it possible to eliminate grid 83. The addition of another electrode complicates the structure although it does increase the tube plate impedance and reduce 20 the waste current. The second method of forming a narrow slot requires a well corrected first electron lens to prevent interception of electrons and thus requires high mechanical accuracy to form the grids. In this case grid 82 is 25 the control grid, the input circuit 86 being connected between the cathode 80 and control grid 82. The output circuit 87 is connected to anode 85.

In Figures 14 and 15 are shown characteristic 30 curves of tubes using the electrode arrangements just described. Figure 14 is the characteristic of a tube incorporating the electrode arrangement shown in Figure 1 and having six beams, and Figure 15 shows the characteristic of a tube 35 incorporating the electrode arrangement shown in Figure 13 and having two beams. It will be observed that in tubes of this type the plate-voltage anode-current characteristics have a sharp knee at a very low anode voltage, a very 40 desirable characteristic for amplifying tubes, particularly power amplifying tubes and oscillators.

The arrangement of electrodes shown in Figure 1 is incorporated in a practical embodiment of my invention which is shown in Figures 8 45 and 9, a plurality of cathodes being used instead of a single cathode as shown in Figure 1, the grids being provided with a plurality of slots registering with the cathode so that in effect the tube is a multiple unit of the construction 50 shown in Figure 1.

The tube in Figures 8 and 9 includes an envelope 20 having a base 21 and a conventional stem and press 22. A mount assembly is supported on the stem by means of the collar 23 55 having the upright supporting rods 24 and 25.

In accordance with my invention the mount includes a plurality of tubular indirectly heated cathode elements 26 (heaters not shown) coated only on opposite sides with emitting coatings 27. 60 This limited application of the emitting material and the use of the bracing fins 28 assist in the formation of beams of electrons from the cathode. Mounted in succession on opposite sides of the cathode are a plurality of slotted 65 rectangular shaped grids including the control grid 29 having rectangular apertures or slots 30 registering with the emitting portions on the cathode elements. This in turn is followed by the screen or accelerating grid 31 having registering apertures 32 and the shield grid 33 provided with apertures 34, the aperture in the grid 31 being the smallest and that in the shield grid 33 the largest. These grids which are of the so-called slat type and best shown in Fig- 75

ures 8 and 9, and in modified form in Figure 11, are mounted on a plurality of insulating rods 40 extending through each of the corners of the grid as shown in Figures 8 and 9, the grids being spaced from each other by means of insulating collars or washers 41 and 41'. The grid assembly is locked in position and the open ends closed by means of the shield members 42 which are welded by means of the ears 43 to the supporting uprights 24 and 25. As best shown in Figure 8a showing the bottom of the mount, the grids on either side of the cathode are electrically connected together in pairs as by means of jumpers 35, 36 and 37, the grids being provided with leads 38, 39 and 37'. Mounted around the cathodes and grids is anode member 44 provided with cooling fins 45.

The grid and cathode element assembly is maintained in spaced relation by means of upper and lower mica spacers 46 and 47 through which the cathodes and the ears on the outer grids 33 extend. Longitudinal movement of the micas is prevented by ears 42' on the shield members 42 extending through and bent down against the surface of the micas as best shown in Figures 8 and 8a. The ceramic rods 40 and collars 41 and 41' could be eliminated and ears placed on each of the grids to extend through mica spacers 46 and 47 to space the cathode and grids but the disclosed construction increases the voltage necessary to cause breakdown between the electrodes due to the better insulating properties of the ceramics at high temperatures and removing high voltages from the mica. This grid and cathode assembly and the anode are in turn maintained in spaced relation by means of the ceramic spacer members 48 at the bottom of the mount and 49 at the top of the mount, the anodes being supported on the anode side rods 50 which are secured to the ceramic spacer members. These ceramic spaced members are secured to support rods 24 and 25 thus supporting the entire mount on these support rods. At the top of the mount assembly is a transverse mica spacer 51 having mounted thereon a plurality of long spring spacers 52 contacting the interior of the envelope to resiliently support the upper end of the mount in the envelope. The anode is connected by means of a lead 53 connected to one of the anode side rods 50 and to the cap 54 at the top of the envelope. Cathode heater wires 55 are electrically connected to the cathode connecting bars 56 which are connected to leads in the press. The shield members 42 electrically connected to the supporting rods 24 and 25 are electrically connected to each other by collar 23.

The spacing between the grids, the size of the apertures and other factors influencing the operation of the tube shown in Figures 8 and 9 are in accordance with the principles set forth above in discussing Figures 1 to 7 inclusive, the construction shown diagrammatically in Figure 1 being the construction used in the practical embodiment of the tube shown in Figures 8 and 9. In the preferred operation of a tube made according to my invention, the first grid is usually the control grid and is at either cathode potential or negatively biased with respect to the cathode. The second grid is positively biased and may be used as a screen or a positively biased control grid. The third grid which functions as a suppressor of secondary electrons and a shield is at zero potential or slightly positive potential with respect to the cathode, but at a lower potential

than the anode which is normally operated at a lower potential than the number two grid. The number one or control grid should not be closer to the cathode than one-half the width of the slots for best results. Close spacing of the electrodes is desirable to obtain a tube in which low voltages can be used. By dividing the total current into a number of beams, the current in each beam is made small enough so that excessive space charge does not build up between the grids and anode and interferes with the beam and limits the anode current. Because a low anode voltage can be used and still obtain high anode current a tube of high efficiency results since little power is dissipated within the tube itself.

A modified form of cathode is shown in Figure 10 and comprises a pair of punched and formed stampings 60 and 61 provided with slots 62 and raised portions 63 which form a plurality of tubular cathode sleeves. These raised portions are provided with an emitting coating 64. Mounted within the cathode is the insulated heater 65 having the separate loops 66, 67 and 68, which are inserted within the tubular members. This cathode is rigid, strong and conserves heat, and is usually made to provide a plurality of separate emitting sections which help in the formation of a beam. The cathode is easy to assemble and reduces the time required for assembly in the tube.

When handling high voltages and high currents it is advisable to have a grid structure in which the separate bars or slats between the slots can contract or expand independently of each other in case of uneven heating. A grid of this kind is shown in Figure 11. The punched and formed grid 70 provided with the slots 71 and the positioning ears 72 and 73 is formed so that the slots 71 extend all the way to the bottom of the grid to a thin lip or ledge 74 at the bottom of the grid. If for any reason the different bars intermediate these slots should be heated to different levels so that expansion is uneven the thin lip which is flexible permits the individual bars to move without affecting the other bars. Uneven expansion of one of the bars does not then cause buckling of the grid bars and short circuiting of the various grids. If it is desired to increase the transconductance of the grid, grid wires may be mounted in the grid transversely of the slots. Such tubes with grid wires on the number one grid frame only have been made and gave very high transconductance values having negligible screen grid current.

In order to facilitate assembly of a tube made according to my invention, I provide a novel grid and mica spacer arrangement for this purpose. As best shown in Figure 12 the grid 75 is provided with the ears or extensions 76 which are pointed. The mica is provided with a plurality of slots for receiving these ears. The slot shown at 78 is provided at its central portion with an enlarged opening 79 which registers with the tip of the ear. This permits quick registry of the grid ears and after they are quickly so registered the mica may be easily pushed down upon the grid without any difficulty. Without these enlarged central portions 79 it would be difficult to insert the grid ears within the slots because of the narrow width of the slots and the ears. The elements may be started by automatic machinery in a fixture with removable spacers and both micas can be assembled, which is not possible in conventional tube mounts.

While I have indicated the preferred embodiments of my invention of which I am now aware and have also indicated only one specific application for which my invention may be employed, 5 it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device including a thermionic cathode, an apertured control electrode for forming the electron discharge from said cathode into a focused beam and means for maintaining said control electrode at a voltage not greater than that of the cathode, a second grid electrode having an aperture registering 10 with the aperture in said control electrode and means for maintaining said second electrode at a positive voltage, and a single anode for receiving electrons in said beam, and means for maintaining said anode at a lower positive potential than 15 said second grid electrode, and a third grid electrode between said anode and said second grid electrode and having an aperture registering with the apertures in the other electrodes, and means for maintaining said third grid electrode 20 at a potential greater than that of the cathode but less than that of the second grid electrode and anode.

2. An electron discharge device having a cathode formed to assist in the formation of a beam 30 of electrons, a control electrode having an aperture coextensive with said cathode and through which electrons pass for forming a focused beam, and means for maintaining said control electrode at a voltage not greater than that of the cathode, a second electrode having an aperture registering with the aperture in the control electrode and positioned so that the beam is focused near the aperture of said second electrode and means for maintaining said second electrode at 40 a positive potential with respect to said cathode, a single anode for receiving the beam of electrons from said cathode, and means for maintaining said anode at a positive potential less than that of said second electrode, and a third electrode between said anode and said second electrode and having an aperture registering with the apertures in the other grids, and means for maintaining said third electrode at a positive potential less than that of said second electrode and anode.

3. An electron discharge device including a thermionic cathode having a plurality of parallel longitudinally extending emitting surfaces, means for forming the electron discharge from said 60 cathode surfaces into a plurality of beams and including a control electrode of sheet material and provided with a plurality of apertures registering with said coated areas on the cathode and coextensive therewith, and a second electrode of sheet material parallel to said first electrode and spaced therefrom and provided with apertures coextensive and registering with the apertures in said first electrode and of larger cross section area than said beams, a single anode for receiving 65 said beams of electrons, and a third electrode positioned between said second electrode and said anode and having apertures registering and coextensive with the apertures in the other electrodes and of an area greater than the width of 70 the beam passing through said last electrode, the

width of the aperture in the first electrode being greater than the aperture in said second but less than that of the aperture in the third electrode.

4. An electron discharge device having means for forming the electron discharge from a cathode into beams of rectangular cross section and including a cathode having a plurality of rectangular shaped parallel coated areas for providing a plurality of electron emitting areas, a single anode for receiving the electrons from said cathode and at least three electrodes positioned between the cathode and the anode and comprising sheet metal electrodes provided with apertures coextensive and in registry with the electron emitting areas of said cathode, the electrode 10 nearest to said cathode being spaced from said cathode not less than one-half the width of the aperture in the electrode nearest to said cathode and forming focused beams which pass through the apertures of the other apertured electrodes to 20 said anode.

5. An electron discharge device having a plurality of beam forming cathode elements, each of said elements comprising a tubular member provided on opposite sides with fins extending 25 beyond the surface of said tubular members, said cathode elements being coated with emitting material only on the surface lying between said fins whereby a beam is formed, a control electrode adjacent said cathode elements and comprising 30 a sheet metal member provided with a plurality of rectangular shaped apertures coextensive and registering with the emitting surfaces of said cathode elements for forming the electrons into focused beams, a single anode for receiving said 35 electrons and a plurality of other sheet metal electrodes positioned between said first control electrode and said anode and provided with a plurality of rectangular shaped apertures in registry with and coextensive with the apertures in 40 said first control electrode, the apertures in said plurality of grids being larger than the cross section of the beams passing through said electrode.

6. An electron discharge device including a cathode for emitting electrons and an anode for receiving said electrons, a control electrode positioned between said cathode and said anode and comprising a sheet metal electrode, one edge of which lies in a plane at an angle to the remainder of said sheet electrode to provide a lip, and apertures in said electrode extending substantially the 50 length of said electrode to said lip whereby the portions of the grid between the apertures may expand and contract independently of each other.

7. An electron discharge device including a cathode, an anode and a control electrode positioned therebetween, said control electrode being of sheet metal and provided at one end with a pointed ear, and an insulating spacer member at one end of said cathode, anode and electrode and having a slot for receiving said pointed ear, said slot being enlarged at that part which registers with the point on said ear to permit quick assembly of said insulating spacer and said control electrode.

8. An electron discharge device including a cathode having a plurality of longitudinally extending electron emitting areas, a control electrode having a plurality of apertures registering with the emitting areas on said cathode for forming a plurality of beams, a second electrode coextensive with said first electrode and spaced therefrom and provided with a plurality of apertures registering with the apertures in said control electrode, a single anode for receiving the beams of 75

electrons from said cathode, a voltage source for biasing said control electrode to a negative potential with respect to said cathode, a voltage source for biasing said second electrode to a positive potential with respect to said cathode, a voltage source for maintaining said anode at a positive potential less than that of the second electrode, and a voltage source for maintaining said third electrode at a positive potential less than that of said second electrode and said anode.

9. An electron discharge device including a thermionic cathode, a control electrode having an elongated aperture for forming the electron discharge from said cathode into a beam, a second electrode having an aperture in registry with the aperture in said control electrode and of an area greater than the cross section of the beam, a third grid electrode having an aperture registering with the apertures in the other grids and a single anode for receiving electrons in said beam, a voltage source for biasing said control electrode to negative potential with respect to said cathode, a voltage source for biasing said second electrode to a positive potential with respect to said cathode, a voltage source for maintaining said anode at a positive potential less than that of the second electrode, and a voltage source for maintaining said third electrode at a positive potential less than that of said second electrode and said anode.

10. An electron discharge device having a cathode formed to provide a beam of electrons, a control electrode having an aperture coextensive with said cathode and an aperture through which the electrons pass for forming a focused beam, a second electrode having an aperture registering with the aperture in said first electrode and positioned so that the beam is focused near the aperture of said second electrode and a third electrode having an aperture registering with the apertures in the other electrodes, a single anode for receiving the electron beam from said cathode, a source of voltage for biasing said control electrode to a negative potential with respect to said cathode, a source of voltage for biasing said second electrode to a positive potential with respect to said cathode, a voltage source for maintaining said anode at a positive potential less than that of the second electrode, and means for maintaining said third electrode at a positive potential less than that of said second electrode and said anode.

11. An indirectly heated cathode having a plurality of spaced parallel emitting surfaces and including a flat member provided with a plurality of longitudinally extending tubular sections with slots in between said sections, electron emitting coatings on said tubular sections, and a continuous insulated heater wire extending within each of the tubular sections.

12. An indirectly heated cathode having a plurality of spaced parallel emitting surfaces and comprising a pair of cooperating members, said members being provided with longitudinally extending sections channel shaped in transverse section and having slots in between said sections and secured together with the longitudinally extending channel shaped sections in registry and cooperating to provide a plurality of tubular sections, an emitting coating on said tubular sections and an insulated heater wire extending within each of the tubular sections.

13. An electron discharge device comprising a plurality of longitudinally extending cathode elements, a plurality of flat slat type grids and insulating bars extending through said grids for

positioning said grids with respect to each other, and insulating washer members carried by said insulating bar for maintaining said grids in spaced relation, U-shaped shield members at opposite longitudinal edges of said grid members for maintaining said grid members assembled on said bars, mica spacer members at the opposite ends of said cathodes, grids and shields for maintaining said cathodes, grids and shields in spaced relation, an anode having side rods surrounding said cathode and grids, ceramic members at opposite ends of said anode and secured to the anode side rods, and supporting rods to which said shield members are secured and to which said ceramic members are secured for maintaining said cathode, grids, shields and anode in spaced relation.

14. An electrode assembly having a cathode and grids and insulating members at opposite ends of said cathode and grids for maintaining said cathode and grids in spaced relation, shield members positioned between and secured to said insulating members, support rods on opposite sides of the grid and cathode assembly and secured to said shield members, an anode surrounding said cathode, grid and shields, and ceramic spacers secured to said anode and to said support rods for maintaining said cathode, grid, shield members and anode in spaced relation.

15. An electron discharge device having a plurality of cathodes and grids, insulating rods extending through said grids for maintaining said grids in spaced relation, insulating spacers at opposite ends of said cathodes and grids for maintaining said cathodes and grids in spaced relation, oppositely disposed shield members adjacent said grids and secured to said insulating spacers for maintaining said cathodes, grids and shield in fixed relationship, a pair of support rods, said shield members being secured to said support rods, an anode surrounding said cathodes and grids, ceramic members secured to opposite ends of said anode and to said support rods for maintaining said cathodes, grids, shields and anode in spaced relation.

16. An electron discharge device having a cathode formed to assist in the formation of a beam of electrons, a first electrode having an aperture co-extensive with the cathode and through which electrons pass for forming a focused beam, a second and third electrode each having an aperture registering with the aperture in the first electrode and positioned so that the beam is focused through the last two apertures, and a fourth electrode having an aperture registering with the apertures in the other electrodes, and a single anode for receiving the electrons from said cathode, the aperture in the first electrode being greater than the apertures in the second and third electrodes but less than that in the fourth apertured electrode.

17. An electron discharge device having a cathode formed to assist in the formation of a beam of electrons, a first electrode having an aperture co-extensive with the cathode and through which electrons pass for forming a focused beam, a second and third electrode each having an aperture registering with the aperture in the first electrode and positioned so that the beam is focused through the last two apertures, and a fourth electrode having an aperture registering with the apertures in the other electrodes, and a single anode for receiving the electrons from said cathode, a voltage source for applying a negative potential to the first electrode

with respect to the cathode, a voltage source for applying a positive potential to the second and third electrodes with respect to the cathode, and a voltage source for applying a voltage to the anode less than that applied to the second and third electrodes, and means for applying a voltage not greater than that of the cathode to the fourth apertured electrode.

18. An electron discharge device having a cathode formed to assist in the formation of a beam of electrons, a first electrode having an aperture co-extensive with the cathode and through which electrons pass for forming a focused beam, a second and third electrode each having an aperture registering with the aperture in the first electrode and positioned so that the beam is focused through the last two apertures, and a fourth electrode having an aperture registering with the apertures in the other electrodes, and a single anode for receiving the electrons from said cathode, a voltage source for applying a negative potential to the first electrode with respect to the cathode, a voltage source for applying a

positive potential to the second and third electrodes with respect to the cathode, and a voltage source for applying a voltage to the anode less than that applied to the second and third electrodes, and means for applying a voltage not greater than that of the cathode to the fourth apertured electrode, the ratio of the positive voltages on the third grid to that on the second grid being 2.5 to 1.

19. An electron discharge device including a cathode, an anode and a control electrode positioned therebetween, said control electrode being of sheet material and provided at one end with a plurality of pointed extensions, and an insulating spacer member at one end of said cathode, anode and control electrode and having slots into which said extensions fit snugly, said slots having an enlarged portion at that part which registers with the points on said extensions to permit quick assembly of the insulating spacer and said control electrode.
